UNITED STATES PATENT OFFICE.

ERNEST C. BEAUMONT, OF BOSTON, MASSACHUSETTS, ASSIGNOR TO UNITED SHOE MACHINERY CORPORATION, OF PATERSON, NEW JERSEY, A CORPORATION OF NEW JERSEY.

METHOD OF RESOLING SHOES.

1,293,672.

Specification of Letters Patent. Patented Feb. 11, 1919.

Application filed March 15, 1918. Serial No. 222,703.

To all whom it may concern:

Be it known that I, ERNEST C. BEAUMONT, a citizen of the United States, residing at Boston, in the county of Suffolk and State of Massachusetts, have invented certain Improvements in Methods of Resoling Shoes, of which the following description, in connection with the accompanying drawings, is a specification, like reference characters on the drawings indicating like parts in the several figures.

The present invention relates to methods of resoling shoes and more particularly to methods of resoling shoes of the type in which the fastenings for attaching the sole to the shoe are received in a part of the shoe located outside the shoe upper; that is, the part of the shoe constituting the extension edge.

For purposes of illustration, the invention is set forth in its application to a shoe of the Goodyear welt type wherein the outsole attaching fastenings are received in a comparatively narrow strip of leather termed a "welt" secured along its inner edge to the inseam of the shoe and extending outside of the shoe upper. It is to be understood, however, that the present invention is equally applicable to types of shoes offering substantially different extensions to receive the outsole attaching fastenings.

In resoling shoes it is invariably found, after detaching the sole from the shoe for the purpose of substituting a repair sole, that the formation of the seam in the welt by which the sole was attached and the wear on the welt have greatly weakened the welt and seriously impaired its further serviceability to attach the repair sole. It is, consequently, essential in attaching the repair sole to the welt to avoid locating the seam in the portion of the welt which received the original seam. Otherwise an insecure attachment of the repair sole would result. This, however, is most difficult and practically impossible, particularly if the portion of the extending welt available for the attachment of the sole is very narrow as in a "close" edge shoe. In fact, it is often found advisable to replace a portion of the welt if not the whole welt on the type of shoes in which this may readily be done, as in a Goodyear welt shoe, before attempting to attach the repair sole, but this involves considerable time and is necessarily hand work. A fur-

ther and important disadvantage of the resoling method heretofore practised is that the sole edge of the resoled shoe cannot be finished so as to secure the desired neat appearance and to eliminate the repaired appearance of the shoe.

The principal object of the present invention is to provide a method of resoling shoes of the general type aforesaid, the practice of which will enable a more efficient and serviceable attachment of repair soles to the shoes than the resoling methods heretofore practised, and which will result in resoling shoes having a much neater and more satisfactory appearance than heretofore.

With this object in view, the present invention provides a method of resoling shoes of the type in which the fastenings for attaching the sole to the shoe are received in a part of the shoe located outside the shoe upper, which consists in applying a repair sole to the shoe, superposing a reinforcing means on the shoe part in which the original sole attaching means was received, and then attaching the repair sole to the shoe by a seam of fastenings passing through said shoe part and anchored in said reinforcing means. In this aspect of the invention and as herein illustrated, a machine-made thread seam constitutes the seam for attaching the repair sole to the shoe, and preferably the reinforcing means which receive and anchor the stitches for securing the repair sole is fed on to the top of the original fastening receiving part simultaneously with the progress of the seam. It will thus be seen that the reinforcing means offers a secure and strong anchorage for the repair sole stitches, thereby insuring a serviceable and durable attachment of the repair sole to the shoe regardless of the weakened condition of the original fastening receiving part, and during the formation of this seam, particularly when machine-made, substantially no care and judgment is necessary to avoid the weakened portions of the said part.

In another of its aspects the present invention contemplates attaching a repair sole to a shoe by a seam of fastenings anchored in an auxiliary welting adapted to cover substantially the entire exposed upper surface of the original fastening receiving part. By utilizing an auxiliary welting strip to receive the repair sole attaching fastenings, the exterior appearance of the extending

sole portion of the repaired shoe is similar to the appearance of the extension sole edge of the original shoe, and it consequently presents a neat and superior appearance.

5 The invention in all of its aspects will now be described in connection with the accompanying drawings which illustrate a preferred practice of the invention, and the invention will then be pointed out in the appended claims.

10 The drawing illustrates in perspective a preferred practice of attaching a repair sole to a shoe in accordance with the present invention.

15 Referring to the drawings, the numeral 2 indicates a Goodyear welt type of shoe, and 4 the original welt which is secured along its inner edge by the inseam stitches 6 to the insole 7 and extends outwardly a distance 20 beyond the sides of the shoe, the extending portion serving to receive the original outsole stitches which attach the outsole to the shoe. The locating of the original outsole stitches are indicated at 8. Although in re- 25 soling a shoe the repair sole may be sewed directly on top of the original sole, it is the usual practice to remove the sole and by the machine repairing methods now employed it is also deemed advisable to remove the entire sole clear back to the heel and substitute an entirely new sole, as distinguished from merely removing the forepart portion of the sole which is commonly known as "tap" resoling. For illustration, the present method 30 will be herein disclosed in connection with the machine process of repairing shoes. Accordingly, the heel of the shoe is removed and the worn sole detached from the shoe by severing the outsole attaching seam 8.

35 40 The formation of this seam in the welt 4, including the awl perforations and the usual wear of the welt, seriously weakens the welt as indicated in Fig. 1, and in order to secure a strong and serviceable attachment of the repair sole to the shoe, it is consequently necessary at one time to form the new seam between the old seam location 8 and the side of the upper and again very near the edge of the welt. This, however, is not practical 45 50 in a great many instances, particularly if the shoe has a close edge; that is, a very narrow extension of welt, with the result that the repairing seam is not as strong and serviceable as desired. If the original welt is so far im- 55 paired as to offer no sewing substance, this portion of the welt is often replaced by a new piece of welt secured to the inseam 6, but this involves considerable time and necessitates considerable hand work which is 60 very often not warranted by the value of the shoe being repaired.

In accordance with this invention, the repair sole 14 is placed in position on the shoe bottom and a reinforcing or auxiliary welt 65 16 is located upon the upper surface of the

welt 4, the auxiliary welt shown being of sufficient thickness to offer a firm sewing substance and of a width to cover the entire exposed upper surface of the welt with its inner edge beveled slightly so as to abut the 70 side of the shoe. Instead of using a leather welt as herein shown, any suitable means or material offering sufficient substance to provide an anchorage for the outsole stitches may conveniently be used. The repair sole 75 14, the original welt 4 and the repair welt 16 are secured together by a seam of stitches 18, and in the preferred practice of the invention the stitches are conveniently formed by a machine of the type shown, for example, in United States Patent No. 473,870, granted April 26, 1892, on application of French & Meyer. The repair welt 16 which is used is guided on to the upper surface of the original welt during the attachment of the repair sole by means of the welt guide 20 of the machine, which insures the proper positioning of the welt against the side of the shoe upper to eliminate any open space between the inner edge of the repair 80 85 welt and the side of the shoe. This repair welt 16 thus receives the repair sole attaching stitches 18 instead of the original welt 4 and provides a firm and strong anchorage for them so that the repair sole 14 is attached to the shoe fully as effectively as the original sole of the shoe. In the use of the sewing machine for the attachment of the repair sole 14, the operator can locate the seam 18 a uniform distance away from the side of 90 95 the shoe completely around the shoe regardless of the location of the original sole fastening seam 8.

Another important consideration with the practice of this method is that the upper 100 surface of the extending portion of the sole or the auxiliary welt 16 presents a neat and uniform appearance as distinguished from the scarred and worn appearance of the surface of the welt 4 resulting from the old practice. Moreover, the edge face of the sole can be trimmed to better advantage without the liability of cutting into the new seam in case the repair sole seam was located outside of the original outsole seam 8 on the welt, 105 110 and a much smoother and better finished sole edge is possible.

115 By the practice of the above described method, particularly in conjunction with the attachment of the repair sole by machine, the time involved in repairing a shoe is greatly reduced and a much more serviceable and satisfactory attachment of the repair sole is obtained. The practice of replacing worn soles of shoes is of growing importance, but because of the questionable serviceability and characteristic "repaired" appearance of resoled shoes due to a large extent to the difficulties above enumerated, the practice of repairing shoes has not been as 120 125 130

extensively resorted to as might be warranted. The practice herein disclosed, however, eliminates the difficulties heretofore encountered and provides an efficient and highly satisfactory manner of repairing shoes.

Having fully described my invention, what I claim as new and desire to secure by United States Letters Patent is:

1. That improvement in methods of resoling shoes of the type in which the fastenings for attaching the sole to the shoe are received in a part of the shoe located outside of the shoe upper, which consists in applying a repair sole to the shoe, superposing a reinforcing means on the shoe part in which the original sole attaching fastenings were receiving, and attaching the repair sole to the shoe by a seam of fastenings passing through the said shoe part and anchored to said reinforcing means.

2. That improvement in methods of resoling shoes of the type in which the fastenings for attaching the sole to the shoe are received in a part of the shoe located outside of the shoe upper, which consists in applying a repair sole to the shoe, superposing a reinforcing means on the shoe part in which the original sole attaching fastenings were received, and then inserting a seam of fastenings to secure together the margin of the repair sole, the said shoe part and the reinforcing means.

3. That improvement in methods of resoling shoes of the type in which the fastenings for attaching the sole to the shoe are received in a part of the shoe located outside of the shoe upper, which consists in sewing a repair sole to the shoe by stitches passing through the margin of the repair sole, the shoe part in which the original sole attaching fastenings were received and into a reinforcing means located on the upper side of the said shoe part.

4. That improvement in methods of resoling shoes of the type in which the fastenings for attaching the sole to the shoe are received in a part of the shoe located outside of the shoe upper, which consists in applying a repair sole to the shoe, superposing a reinforcing welt upon the shoe part in which the original sole attaching means was received, and then attaching the repair sole

to the shoe by a seam of fastenings passing through the said shoe part and anchored in the said reinforcing welt.

5. That improvement in methods of resoling shoes of the type in which the fastenings for attaching the sole to the shoe are received in a part of the shoe located outside of the shoe upper, which consists in detaching the worn sole from the shoe and replacing it with a repair sole, superposing a reinforcing welt upon the upper side of the shoe part in which the original sole attaching stitches were received with its inner edge abutting the shoe upper, and then sewing the repair sole to the shoe by a seam of stitches passing through the margin of the repair sole, the said shoe part and the reinforcing welt.

6. That improvement in methods of resoling shoes of the type in which the fastenings for attaching the sole to the shoe are received in a part of the shoe located outside of the shoe upper, which consists in detaching the worn sole from the shoe and replacing it with a repair sole, and then attaching the repair sole to the shoe by a seam of fastenings passing through the margin of the repair sole and the shoe part in which the original sole attaching fastenings were received, and simultaneously supplying a reinforcing means to the upper side of the said shoe part to provide an anchorage on the said shoe part for the repair sole attaching fastenings.

7. That improvement in methods of resoling shoes of the type in which the fastenings for attaching the sole to the shoe are received in a part of the shoe located outside of the shoe upper, which consists in detaching the worn sole from the shoe and replacing it with a repair sole, and then sewing the margin of the repair sole to the shoe part in which the original sole attaching stitches were received by a continuous thread seam, and simultaneously supplying a reinforcing welt to the upper side of the said shoe part with its inner edge abutting the shoe upper to receive the stitches passing through the said shoe part.

In testimony whereof I have signed my name to this specification.

ERNEST C. BEAUMONT.

It is hereby certified that in Letters Patent No. 1,293,672, granted February 11, 1919, upon the application of Ernest C. Beaumont, of Boston, Massachusetts, for an improvement in "Methods of Resoling Shoes," an error appears in the printed specification requiring correction as follows: Page 3, line 18, claim 1, for the word "receiving" read *received*; and that the said Letters Patent should be read with this correction therein that the same may conform to the record of the case in the Patent Office.

Signed and sealed this 25th day of November, A. D., 1919.

[SEAL.]

M. H. COULSTON,

Acting Commissioner of Patents.
